CLAIM

The ornamental design for a step-stool, as shown and described.

DESCRIPTION

FIG. 1 is a perspective view of a step-stool showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom side perspective view thereof; and,

FIG. 9 is a perspective view of the step-stool of FIG. 1, shown with unclaimed patterned ornamentation.

The broken lines in the drawings depict portions of the step-stool that form no part of the claimed design.
